UNITED STATES PATENT OFFICE.

ELBERT H. CARROLL, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

CLUTCHING MECHANISM FOR WIRE-DRAWING BLOCKS.

Application filed February 19, 1919. Serial No. 277,919.

To all whom it may concern:

Be it known that I, ELBERT H. CARROLL, a citizen of the United States, residing at Worcester, in the county of Worcester and 5 Commonwealth of Massachusetts, have invented a new and useful Improvement in a Clutching Mechanism for Wire-Drawing Blocks, of which the following, together with the accompanying drawings, is a specification.

The present invention relates in general to wire drawing blocks, and in particular to a frictional clutching means adapted to be operated to connect said block, or other 15 driven member, with its driving shaft. The invention resides in a novel combination and arrangement of power transmitting instrumentalities including an expandible friction coil, introduced between the driving 20 and driven members of the mechanism, and adapted to establish, when desired, an operative connection therebetween.

The invention is fully set forth in the following description and pointed out in 25 the annexed claims, reference being had to the accompanying drawings, wherein—

Fig. 1 is a side view, partly in section, of 30 a wire drawing block and its driving means, suitable for the application of the invention thereto, and

Fig. 2 is a sectional view, on an enlarged 35 scale, showing the improved clutching device as applied to the interior of the wire drawing block of Fig. 1.

Like reference characters refer to like 40 parts in the different figures.

Referring to Fig. 1, the numeral 1 designates the supporting framework, below 45 which is journaled a horizontal driving shaft 2. The latter serves, through bevel gears 3, 4, for the rotation of a vertical spindle 5 which is suitably journaled in the framework 1. As usual in devices of this class, the constantly rotating spindle 5 is arranged so as to transmit its rotation, when desired, to the wire drawing block 6; to this end, it is the usual practice to dispose the block for vertical sliding movement on the spindle to provide for the lifting 50 of said block by means of rolls 7, 7 carried in arms 8 of a pivoted yoke 9. The rolls 7, 7 cooperate with an annular track 10 at the bottom of the block 6, and when arm 11 of yoke 9 is depressed, by reason of

its connection to a foot treadle 12 or the like, 55 the block 6 is lifted slightly, for the purpose of disengaging the driving connection that it makes with the spindle 5. When the treadle is released, the block 6 descends by gravity and the clutch or other driving connection again becomes operative to cause the rotation of said block with said spindle.

The present invention resides in the provision of an improved form of clutching device between the block 6 and the spindle 60 5, which device lends itself readily to the method of operation above specified, and at the same time is of such a character as to inaugurate the rotation of the block without the shock and jar to the mechanism that 65 usually occurs in devices of this class. As shown in Fig. 2, the block 6 has an interior cylindrical portion 13, which surrounds and is spaced from the spindle 5. At its upper end the cylindrical portion 13 is contracted 70 to form a guide bearing 14 through which the spindle 5 projects, and by means of which the block 6 is guided in its vertical movement relative to said spindle.

Within the recess inclosed by the cylindrical portion 13, the spindle 5 has rigidly secured thereto a block or collar 15, which is held in place by a pin or other suitable retaining means 16. Also surrounding the spindle 5 within the space inclosed by cylindrical portion 13 is a member 17, which is superposed on block or collar 15. The member 17 is loose on the spindle 5, but is prevented from moving endwise, away from the block or collar 15, by any suitable means, 80 such as a pin 18.

The block 15 and member 17 are surrounded by a spirally wound continuous coil 19, having at one end a projection 20 engaged in a groove 21 of block 15, and 85 having at the other end a projection 22 engaged in a groove 23 of member 17. As herein shown, the portion of member 17 which is surrounded by coil 19 is slightly tapered downwardly to approximately the same diameter as the block 15, and the surrounding convolutions of coil 19 are preferably made to conform to this taper on their inner surfaces which make contact with said member 17; the outer surfaces of said 90 convolutions conform to the wall of cylindrical portion 13, from which they are normally slightly spaced.

The member 17 at its upper end provides a frusto-conical friction surface 24 which is adapted for cooperation with the correspondingly bevelled interior surface 24' of cylindrical portion 13. In the normal position of the parts, when the block 6 is raised by rollers 7, as shown in Fig. 2, the surfaces 24 and 24' are separated slightly, so that there is no tendency for the block 10 to be rotated by the spindle 5 or by any of the parts carried by said spindle within the recess surrounded by cylindrical portion 13. Under these conditions, the coil 19 hugs the block 15 and member 17, and the 15 latter thereby rotates freely in unison with the spindle 5.

When the block 6 is lowered by the release of treadle 12, the surfaces 24 and 24' come into frictional contact, and the weight 20 of the block, together with its resistance to rotation imposes an immediate drag on member 17. As a result, the latter no longer rotates in unison with the block 15, and this difference in movement between the two 25 parts to which the opposite ends of coil 19 are connected, obviously causes the spreading or expansion of said coil, so that the outer surfaces of its convolutions are pressed with increasing force against the wall of 30 cylindrical portion 13. The rotation of block 15 is thus transmitted through the coil 19 to the wire drawing block 6, and it will be obvious that the frictional holding power or expansion of the coil increases in 35 proportion to the amount of power which the mechanism is called upon to transmit. In other words, as the resistance to the rotation of the block increases, the force tending to expand the coil 19 increases also, thus 40 eliminating slippage or the loss of power. It will also be clear that with the provision of a clutching device of this nature, the starting movement of the wire drawing

block is relatively gradual and easy, with no tendency to jerk the wire, or to impose 45 any sudden stress or shock on the mechanism. In order to minimize the wear on portion 13, which is caused by the band 19, said portion 13 may be lined with a hard steel 50 bushing 25, as shown in Fig. 2.

I claim,

1. The combination, with a wire drawing block, of a driving spindle therefor, and a clutching means interposed between said block and said spindle, said clutching means 55 comprising a coil rotating with said spindle and adapted to be expanded into frictional engagement with the interior of said block by axial movement of the latter.

2. The combination with a rotating 60 spindle, of a wire drawing block providing an internal friction surface, and a coil attached to said spindle and adapted to be expanded into frictional contact with said surface by axial movement of said block, in 65 the act of transmitting to said block the rotation of said spindle.

3. The combination with a driving member, of a spiral band adapted to rotate therewith, a tapered loose member operatively 70 connected to one end of said band, said band being tapered internally to conform to the surface of said loose member, a driven member surrounding said band, and presenting an internal friction surface conforming to 75 the external surface of said band, and means for imposing the drag of said driven member on said loose member, whereby to expand said band into driving engagement with said internal friction surface. 80

Dated this fourteenth day of February, 1919.

ELBERT H. CARROLL.
